UNITED STATES PATENT OFFICE.

INGENUIN HECHENBLEIKNER, OF CHARLOTTE, NORTH CAROLINA, ASSIGNOR TO SOUTHERN ELECTRO-CHEMICAL COMPANY, OF NEW YORK, N. Y., A CORPORATION OF NEW JERSEY.

ELECTRIC-FURNACE-WALL CONSTRUCTION.

1,217,306.

Specification of Letters Patent. Patented Feb. 27, 1917.

Original application filed November 2, 1914, Serial No. 869,830. Divided and this application filed September 27, 1915. Serial No. 52,863.

To all whom it may concern:

Be it known that I, INGENUIN HECHENBLEIKNER, a subject of the Emperor of Austria-Hungary, and resident of Charlotte, in the State of North Carolina, United States of America, have invented certain new and useful Improvements in Electric-Furnace-Wall Construction, of which the following is the specification.

10 This invention relates to improvements in electric furnace wall construction and is especially designed for use in connection with the treatment of phosphate rock to expel phosphoric acid, and the objects of the 15 invention are to overcome the peculiar difficulties present by the extremely high temperature of the slag formed in this process, and it consists essentially of the improved construction hereinafter described in detail 20 in the accompanying specification and drawing.

The drawing shows a vertical section through an embodiment of the invention.

The details of the electrodes and other 25 features of the furnace constructed apart from the walls thereof are shown in my application Serial No. 869,830, filed November 2nd, 1914, of which this is a division.

30 The electric furnace itself may, in the present invention, be said to consist of three parts comprising the bottom section A, the tapered stack section B and the outlet elbow C. These parts are detachably connected and fit together, the detachable connection between the bottom portion and tapered stack section being effected by abutting channel sections 10 and 11 which are bolted or otherwise clamped together while the detachable connection between the tapered stack section and the elbow section is effected by similar channel steel sections 12 and 13 which are similarly connected together.

35 The bottom section A is water-cooled and is, in fact, practically in the form of a water jacket, being formed with inner and outer walls 14 and 15 of thin sheet metal separated and connected together by I-beams 16 or the like and having means for circulating 40 water in the interior and distributing the same equally therethrough.

To effect an even distribution of water, an annular outlet channel 17 is formed

around the top on the exterior into which equally distributed overflow pipes 18 are 55 arranged to discharge, such overflow pipes extending in a radial direction from the interior of the water jacket.

The inflowing water is adapted to pass through a conduit 19 which opens at the top 60 of the water jacket.

The furnace is originally constructed without any lining in the bottom section whatever. The water jacket, however, being considerably cooler than the slag formed 65 within the furnace will cause a portion of the slag to freeze to the inner wall of the water jacket to thereby form a lining D of frozen slag.

It is found that a lining of this character is the only one which will resist the action of the calcium silicate slag. It is impracticable to use any form of fire-brick or other lining generally used in electric furnaces, owing to the fact that such lining 70 will be readily attacked by the phosphoric acid and calcium silicate slag.

The body portion rests on suitable transverse bearings 20 conveniently formed of wood or like insulating material. On one 80 side of the body portion a slag overflow E is provided which is kept open during the operation and which is so arranged that the molten slag seals the furnace.

Suitable manholes 25 are also formed 85 around the body portion having water cooled doors 26, the inner sides of the water cooled doors being covered with a layer of frozen slag.

The tapered section B of the furnace is 90 not water cooled and is adapted to carry the electrodes F which extend in an inclined direction through it.

The electrodes and the holders and means for adjusting the electrodes do not form 95 part of the present invention and are disclosed in my aforesaid application Serial No. 869,830.

In practically using the invention in the manufacture of phosphoric anhydrid from 100 which phosphoric acid may be made, suitable quantities of natural phosphate rock, silicious material and carbon are mixed together and fed to the electric furnace. An alternating current is preferably used.

105 The heat of the arc and the resistance heat

developed within the furnace will expel phosphoric acid and phosphorous vapor from the furnace mixture, leaving a calcium silicate slag which as it accumulates will 5 overflow through the slag overflow E. The phosphorous and phosphoric anhydrid expelled from the furnace gases will be suitably oxidized and caught by suitable absorption towers, such for example as those shown 10 in my United States Patent Number 1,112,211, granted on September 29th, 1914.

The walls of the body portion will be effectively protected from the action of the slag and phosphoric acid by the layer of molten 15 slag which will form on it.

In the process as above described a comparatively high voltage (say in the neighborhood of 300 volts) is necessary for a successful operation, and experiments made 20 have proved that it is impossible to use any type of well known furnace lining with a voltage as high as this and with a slag having the high temperature of the calcium silicate slag produced in the process. It is 25 found, however, that the water cooled furnace walls chill the slag to form an effective protective coating as above described.

What I claim as my invention is:

1. An electric furnace comprising a water cooled body, a non-water cooled tapered 30 portion connected to the body portion, a non-water cooled elbow section connected to the tapered portion, and a lining of chilled slag of substantially uniform thickness for both the water cooled and non- 35 water cooled parts.

2. An electric furnace comprising a water cooled body portion, a lining of chilled slag extending completely around the sides and over the bottom of the body portion, a tapered portion fitting on the body portion, a detachable connection between the tapered portion and body portion formed by channel 40 steel sections bolted together, and an elbow section connected to the tapered section, a pair of channel steel sections forming the connection between the tapered section and the elbow section. 45

In witness whereof I have hereunto set my hand in the presence of two witnesses.

INGENUIN HECHENBLEIKNER.

Witnesses:

D. C. CARMICHAEL,
A. M. WEBB.
